UNITED STATES PATENT OFFICE.

CHARLES HENRY BACON, OF DANIELSON, CONNECTICUT.

ROD-HANGER FOR WINDOW-SHADES.

SPECIFICATION forming part of Letters Patent No. 697,313, dated April 8, 1902.

Application filed May 11, 1901. Serial No. 59,816. (No model.)

To all whom it may concern:

Be it known that I, CHARLES HENRY BACON, a citizen of the United States, and a resident of Danielson, in the county of Windham and 5 State of Connecticut, have invented a new and Improved Combined Rod-Hanger and Clamp for Window-Shades, of which the following is a full, clear, and exact description.

The object of the invention is to provide 10 a new and improved rod-hanger for window-shades which is simple and durable in construction, arranged to form a permanent part of a shade, and is easily placed and secured in position on the window-frame to support 15 and hold the shade in proper position relatively to the window and which hanger also serves as a binder or clamp to hold the shade-cloth wound up on the roller when the window-shade is in stock at a dealer's store and 20 forms therewith a permanently attached and complete article of manufacture.

Figure 1 is a front elevation of the improvement as applied to a window. Fig. 2 is an enlarged view of one end of the device. Fig. 25 3 is a like view of the other end, and Fig. 4 is an enlarged perspective view of the rod-hanger and shade detached from the window, but permanently connected together and forming a separate article of manufacture.

30 The improved rod-hanger for window-shades consists of a rod A, supporting at its ends the hangers B B' for the trunnions C C' of a roller D, carrying the shade-cloth E. The hangers B B' are each made of a piece of wire bent to form pendent loops for the trunnions C C', as will be readily understood by reference to Figs. 2 and 3, and said loops are extensions from coils B², firmly engaging the ends of the rod A, so as to hold the hangers 35 securely in position on said rods without other fastening devices.

The coils B² have the natural elasticity of helical springs and, with their hangers, are simply turned by a rotary screwing movement on the ends of the rod A, so that no cutting or fitting of the rod A is required at the ends and no set-screws or other parts which are liable to become loose are employed. The spiral convolutions also give to the ends of 45 50 the rod the ornamental effect of terminal thimbles or caps. The most important feature of this special form of helical-spring

hanger and rod, however, is that the convolutions of the coils B² and the natural spring of the same and of the roller-trunnion C are 55 such as to make the entire length of the rod A to lie flat and parallel against the window-shade when rolled up, as in Fig. 4, and thus clamp and hold it against becoming unrolled and soiled or torn when kept in stock in the 60 store, the rod A and helical-wire hangers being permanently attached to the roller and shade and forming a part thereof as a unitary article in both the manufacture and sale as 65 well as in the use of the same.

In applying my invention to a window the rod A may be detachably secured thereto in any desired way. A very simple and inexpensive means consists of screw eyes or hooks F, screwing into the window-frame G and receiving in their eyes or loops the rod A to support the latter, and consequently the window-shade, in proper position on the window-frame.

As is usual with spring-rollers of the Harts-horn type, one trunnion C is flattened and requires to be rigidly held against rotation. The elongated and flattened loop B accomplishes this at one end, while the other loop allows the other trunnion to rotate freely. 80 These conditions are provided for in the most simple and inexpensive manner.

The device is very simple, cheap, and durable in construction, and as it forms a permanent fixture of the window-shade it is evident that the latter can be quickly and conveniently attached to the window-frame in any desired position.

Having thus described my invention, what I claim, and desire to secure by Letters Patent, is—

1. A hanger-rod for window-shade rollers having at each end a hanger for the roller-trunnion consisting of several helical convolutions of wire binding thereon by elastic constriction and forming at each end a terminal ornamental head, one end of the wire in each hanger being extended and bent into a loop to receive the shade-roller trunnion, substantially as and for the purpose described.

2. A new article of manufacture comprising a shade-roller with trunnions and a shade wound upon the roller, and a hanger-rod extending parallel to the shade-roller and bear-

ing at each end a terminal coil consisting of convolutions of wire binding thereon by elastic constriction and also forming ornamental heads, one end of said wire being extended and bent into a loop to receive the shade-roller trunnion, said rod being held by its helical-spring hangers in elastic contact with the rolled-up shade across its width to clamp and hold the end of the same against unroll-

ing substantially as and for the purpose described.

In testimony whereof I have signed my name to this specification in the presence of two subscribing witnesses.

CHARLES HENRY BACON.
